UNITED STATES PATENT OFFICE.

EDWARD J. GLACKIN, OF CHICAGO, ILLINOIS.

CUSHION MECHANISM.

1,418,912.

Specification of Letters Patent. Patented June 6, 1922.

Application filed March 7, 1921. Serial No. 450,242.

To all whom it may concern:

Be it known that I, EDWARD J. GLACKIN, a citizen of the United States and a resident of Chicago, in the county of Cook and State of Illinois, have invented certain new and useful Improvements in Cushion Mechanism, of which the following is a full, clear, and exact specification.

My invention is concerned with shock absorbers, and is designed to produce a simple and efficient device of the class described which I have shown as particularly adapted to be employed upon a motor car.

It is further concerned with shock absorbers so mounted between the body and the chassis of a car that the body is free to sway sidewise within its intended limits, without in any way interfering with the operation of the absorbers.

It is finally concerned with certain simple and novel fittings whereby such shock absorbers may be quickly and easily applied to the chassis and body of a motor car as supplementary to the springs with which it is initially equipped.

To illustrate my invention, I annex hereto three sheets of drawings in which the same reference characters are used to designate identical parts in all the figures of which—

Fig. 1 is a side elevation in dotted lines of a vehicle having my improved shock absorber applied thereto in the manner shown in the full lines of said figure;

Figs. 2 and 3 are similar views, but on an enlarged scale, of a portion of the machine as seen in front and rear elevations;

Fig. 4 is a similar view in section on a still larger scale on the line 4—4 of Fig. 2;

Fig. 5 is a plan view in section on the line 5—5 of Fig. 4;

Fig. 6 is an enlarged detail of a portion of the mechanism shown in Fig. 4;

Fig. 7 is an enlarged detail in section on the line 7—7 of Fig. 2;

Fig. 8 is a similar enlarged detail in section on the line 8—8 of Fig. 3;

Fig. 9 is a top plan view of a portion of one of the shock absorbers applied to the rear axle; and

Fig. 10 is a detail in section, on an enlarged scale, on the line 10—10 of Fig. 9.

In illustrating my invention, I have shown it as applied to a well known type of machine in which the body 11 has at its front end the supporting cross beam 12,

which is of inverted U-shape in cross section, and has the bow spring 13 secured at its center in the cross beam by the U-bolts 14. At the ends of the bow spring are the links 15 by which the ends of the spring are connected to the supports 16 secured to the front axle 17, so that the front of the body is free to sway from side to side within the limit permitted by the employment of the links 15. At the rear is a cross beam 18, of an inverted U-shape in cross section, and having the curved central portion 19 in which is placed the similarly curved central portion of the bow spring 20 which is connected at its ends by the links 21 with the brackets 22 projecting inwardly from the upper ends of the shallow cylinder casings 23 secured to the ends of the hollow tapered axle 24 having the customary differential gear casing 25 at its center. It will of course be understood that the structure thus far described is old and well known, and per se, forms no part of my invention.

The shock absorber units each comprises a cylinder portion 26, preferably made of metal, and having its lower end closed air-tight by a casting 27, which preferably takes the form of a bracket, as subsequently described, and has in its upper surface the annular seat 28 in which the lower end of the cylinder 26 is brazed or soldered, or otherwise secured to make an air-tight joint. On the under side of the bracket is a downwardly projecting annular flange 29, which is employed to protect the valve 30 secured in the bottom of the cylinder and by which the air inside can be compressed. The upper end of the cylinder is preferably provided with an enlargement 31, which takes the form of an annular flange having its upper portion internally threaded, so as to be engaged by the clamping ring 32 having the lower portion of its exterior threaded and its upper portion 33 preferably hexagonal in its horizontal outline so that a wrench can be readily applied thereto. In the space between the top of the cylinder 26 and the flange 31 is an annular seat 34, which, as best seen in Fig. 6, is preferably rectangular in its vertical cross section, and is adapted to receive the lower portion of the annular flange 35 forming the bottom of the dome shaped cap 36, which is preferably formed of rubber, reinforced with canvas or some other suitable fiber to give it increased dura-

bility. The flange 35 is connected with the generally semicircular body portion of the cap by a neck 37, which rests on the top of the cylinder 26, and is squeezed between it and the downwardly projecting annular flange portion 38 of a clamping ring 39, the under surface of which is shaped to cooperate with the neck 37 and the upper portion of the flange 35. Its top is flat, and is engaged by the bottom of the ring 32, the inner surface 40 of which is curved to correspond with the dome shape assumed by the rubber cap 36, said cap having its normal shape that of a dome, and this being of course enlarged somewhat when the cylinder is inflated through the valve 30.

I have found by experiment with a similar cylinder and dome shaped cap that when it is strongly inflated and when a heavy pressure is applied thereto by the plunger to be hereinafter described, there is a very strong tendency for the flange 35 to pull out of its seat by being compressed and turned at right angles to its normal shape, and to remedy this, I insert in the flange 35, the metal ring 41, which is preferably a strip of spring steel and of the same general outline in cross section as the flange in which it is embedded when the cap is molded. I have found that the employment of this ring absolutely prevents any possibility of the dome being pulled out of its place, and when the parts are assembled, as shown, and the ring 32 is screwed down tight, an air-tight joint is produced, and I usually further insure this joint being air-tight by dipping the flange 35 in a liquid cement before it is seated in the channel 34. Cooperating with the dome or cap 36 is the head 42 of the plunger, which is preferably a heavy metal disk with its under side rounded, as shown, and supported by the threaded rod 43 screwed into the recess in the bottom thereof. The upper end of the rod 43 passes through an aperture in the bracket casting 44, which will have a shape to be described, and on the upper end I screw the nut 45 to firmly clamp in place the washers 46, which may be of any desired material, and which are preferably of different thicknesses so that they can be adjusted to a nicety to cause the curved under surface of the head 42 to rest lightly on the top of the cap 36 when the absorbers are secured on the vehicle and the same contains its average load.

The bracket 27 for the cylinders used with the front of the machine has the extension 47, best seen in Figs. 4 and 5, which extension is provided with the upwardly projecting lugs 48 and 49, which form a seat for the bottom of the axle 17, which is in the general form of an I beam, of varying heights, however. The extension 47 is provided with four apertures suitably located

to receive the lower ends of the pair of U-bolts 50, embracing the axle and having their threaded lower ends receiving the nuts in the customary manner. I may employ between the two sets of bolt holes the downwardly extending strengthening rib 51. The bracket 44, as seen in Figs. 2, 4 and 7, has the rearwardly extending portion preferably provided with the strengthening rib 52 through an enlargement 53 of which extends the aperture for the bolt 43. This rearwardly extending portion of the bracket 44 has the downwardly and inwardly inclined portion 54, which is provided with the seat for the end of the cross beam 12, on either side of the pair of upwardly projecting ribs 54^a and also with the lugs 55 provided with the apertures for the U-bolt 56 extending therethrough and over the cross beam 12. Associated with the forward portion of this bracket is the U-bolt 57 passing through apertures in the bracket and which fits over an extension of or an attachment 57^a to the cross beam 12 in the manner seen. With this construction, it will be obvious that the plunger 42 can be mounted on each end of the cross beam 12 without in any way interfering with its original construction and mode of operation, and similarly the bracket 27 can be mounted on the axle so as to bring the caps 36 directly beneath the plungers simply by applying the parts to the axle and placing and securing the U-bolts.

For the rear axle, I provide the castings 58, best seen in Figs. 8, 9 and 10, and the parts cooperating with the cylinders 26 are the same as the brackets or castings 27. The extension, however, is provided with the pair of upwardly extending projections 59 and 60, the inner surfaces of which and the connecting portion form the semicircular seat for the tapering hollow axle 24, and the bracket 58 has on either side of these projections 59 and 60 the pair of apertures to receive the U-bolts 61 cooperating with the axle and the bracket in the customary manner. As the cylindrical and tapered form of the axle 24 would render it difficult to keep the parts in place, I form on the bracket 58 an extension 62 having an aperture therein through which I pass the bolt 63, which also passes through an aperture in the end of the brace bar 63' which has secured in its end a U-bolt 64 through which passes the brace rod 65 extending from the casing 23 forward to the rear of the chassis. The employment of this brace rod serves to anchor the bracket 58 in position, and said bracket and the brace bar 63 can be applied to the machine as it stands. Cooperating with the cylinders on the rear axle are the same plungers 42 having, however, the longer rods 43 and stem washers 46, and the upper ends of the rods pass through aper-

tures in the brackets 65, which like the brackets 44 have the generally right angular shape, but with the inwardly projecting portions 66 of a shape adapted to fit into the open under sides of the cross beam 19 with their inner ends resting on the cross pieces 67, which form a part of said cross beam 19. A bolt 68 is passed through an aperture in the portion 66 of the bracket and also through an aperture which exists in the top of the cross beam 18, thus serving to secure the rear plungers in place and ready to cooperate with the caps 36.

It will be obvious that with the construction shown, the plungers 42 can have a considerable amount of lateral play without getting off of or out of cooperative relation with the caps 36, so that these shock absorbers can be added to the machine without interfering in any way with its operation, as the body from time to time is still free to sway sidewise relative to the chassis as much as the use of the links 15 and 21 will permit.

While I have shown and described my invention in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is—

1. In a vehicle, the combination with a chassis, of a body, bow springs interposed between the axles and the body, link connections between the ends of the springs and the axles, two pneumatic cylinders having dome-like flexible tops attached to each of said axles toward the sides of the body, and a plunger having a rounded end cooperating with each of the tops of the cylinders so that they can move transversely relative thereto, said plungers secured to the ends of the body beams to which the centers of the bow springs are secured.

2. In a vehicle, the combination with a chassis, of a body, bow springs interposed between the axle and the body, two pneumatic cylinders attached to each of said axles toward the sides of the body, a plunger cooperating with each of the cylinders, said plungers being secured to the ends of the body beams to which the centers of the bow springs are secured, brace rods extending from the ends of the rear axle to the reach, and tie pieces extending from the base of the rear cylinders to the brace rods.

3. In a vehicle, the combination with a body having transverse beams, inverted U-shape in cross section, secured to the front and rear thereof, of a chassis, bow springs secured at their centers in the transverse body beams, connections between the ends

of the bow springs and the two axle bars permitting transverse movement of the body relative to the chassis, downwardly extending plungers supported from the ends of the body beams and moving transversely therewith, and pneumatic cylinders supported from the axles and extending upwardly therefrom directly beneath the plungers which cooperate therewith and can move transversely thereof within the limits of the transverse movement permitted by the spring connections.

4. In a vehicle, the combination with a body having transverse beams, inverted U-shape in cross section, secured to the front and rear thereof, of a chassis, bow springs secured at their centers in the transverse body beams, connections between the ends of the bow springs and the two axle bars, downwardly extending plungers supported from the ends of the body beams, pneumatic cylinders supported from the axles and extending upwardly therefrom directly beneath the plungers which cooperate therewith, and brackets connected to the plungers and cylinders and shaped so as to be secured by U-bolts to the body beams and axles.

5. In a vehicle, the combination with a rear axle, of a pneumatic cylinder having its base formed with a bracket adapted to fit to the under side of the axle, a U-bolt cooperating with the axle and the bracket to secure the latter in place on the axle, a brace rod extending from the end of the axle to the reach, and a tie piece secured to the bracket and the brace rod for the purpose described.

6. In a device of the class described, the combination with an air-tight metallic cup closed at the bottom, said cup being provided at its top with an annular channel, of a flexible dome-like cap adapted to be seated in said channel and to be reversed into the cup, the portion of said cap entering the channel being provided with a metallic ring embedded therein for the purpose described, and a ring secured on the top of the cup and holding the cap in place forming an air-tight joint between it and the cup for the purpose described.

7. In a device of the class described, the combination with an air-tight metallic cup closed at the bottom, said cup being provided at its top with an annular channel, of a flexible dome-like cap adapted to be seated in said channel and to be reversed into the cup, the portion of said cap entering the channel being provided with a metallic ring embedded therein for the purpose described, said ring being elongated in cross section parallel to the axis thereof, and a ring secured on the top of the cup and holding the cap in place forming an air-tight joint between it and the cup for the purpose described.

8. In a device of the class described, the combination with an air-tight metallic cup closed at the bottom, said cup being provided at its top with an annular channel and 5 at the bottom having a bracket formed integrally therewith by which it may be secured to the axle of a vehicle, of a flexible dome-like cap adapted to be seated in said channel and to be reversed into the cup, and a ring 10 secured on the top of the cup and holding the cap in place forming an air-tight joint between it and the cup for the purpose described.

9. In a device of the class described, the 15 combination with an air-tight metallic cup closed at the bottom, said cup being provided at its top with an annular channel and at its bottom with means for securing it to the axle of a vehicle, of a flexible dome-like 20 cap adapted to be seated in said channel and to be reversed into the cup, a ring secured on the top of the cup and holding the cap in place forming an air-tight joint between it and the cup for the purpose described, a 25 rounded head adapted to cooperate with the top of the cap, a stem for said head, and means for securing the stem to the body of a vehicle.

10. In a device of the class described, the 30 combination with an air-tight metallic cup closed at the bottom, said cup being provided at its top with an annular channel and at its bottom with means for securing it to the axle of a vehicle, of a flexible dome-like 35 cap adapted to be seated in said channel and to be reversed into the cup, a ring secured on the top of the cup and holding the cap in place forming an air-tight joint between it and the cup for the purpose described, a 40 rounded head adapted to cooperate with the top of the cap, a stem for said head, and a bracket secured to the stem and adapted to be secured to the body of the vehicle.

11. In a device of the class described, the 45 combination with an air-tight metallic cup closed at the bottom, said cup being provided at its top with an annular channel and with threads, of a flexible dome-like cap adapted to be seated in said channel and to be reversed into the cup without engaging the 50 walls thereof, and a ring screwed on to the end of the cup and securing the cap in place forming an air-tight joint between it and the cup for the purpose described, said ring 55 having its upper inner portion shaped to fit complementarily on the expanded cap.

12. In a device of the class described, the combination with an air-tight metallic cup closed at the bottom, said cup being provided 60 at its top with an annular channel and at its bottom with a pneumatic valve, of a flexible dome-like cap adapted to be seated in said channel and to be reversed into the cup, and a ring secured on the top of the cup and 65 holding the cap in place forming an air-tight

joint between it and the joint for the purpose described, the bottom of the cup having a bracket formed integrally therewith by which it may be secured to the axle of a vehicle, said bracket having a downwardly extending flange surrounding the valve to protect it. 70

13. An air cushion comprising a metallic cylinder having one end closed air-tight and the other end provided with a screw thread 75 on its rim and an inwardly extending flange forming an annular channel between it and the rim, an elastic, comparatively shallow dome-shaped cup thick enough to make it self-supporting, adapted to have its body inverted into the cylinder and having an enlarged rim fitting into the annular channel, a gasket nut screwed on to the cylinder to press the rim into the channel to make an air-tight joint under high pressure and prevent it being pulled out by said pressure, a plunger materially less in diameter than the diameter of the cup cooperating therewith, and an inflation valve connected to the metallic cup. 80

14. An air cushion comprising a metallic cylinder having one end closed air-tight and the other end provided with a thread on its rim and a flange extending inwardly forming an annular channel between it and the 95 rim, an elastic cup adapted to have its body forced into the cylinder and having an enlarged rim fitting into and entirely filling the annular channel and above it an annular surface, a metallic washer resting on said surface, a gasket nut screwed on to the rim and engaging the upper surface of the washer for the purpose described, and an inflation valve for the cylinder. 100

15. In a shock absorber for vehicles, the combination with a support adapted to be secured to a chassis, of an opposed support adapted to be secured to a body, a rigid metallic cup secured to and projecting from one support and having an edge of its rim 110 threaded and provided below said threaded edge with a flange extending inwardly, a rubber cup having its soft enlarged rim shaped to fit snugly into and entirely fill the annular recess formed between the flange 115 and the adjacent wall of the cup, and having an external annular flange surface, a gasket nut threaded into the top of the metallic cup and having its bottom adapted to compress the soft rubber rim into the annular recess to make an air-tight joint, connections between the supports to permit them to be moved toward and from each other within certain limits, an inflation valve connected to the metallic cup, and a plunger carried 125 by the other support and cooperating with the top of the rubber cup, substantially as and for the purpose described. 120

16. In a device of the class described, the combination with an air-tight metallic cup 130

closed at the bottom, said cup being provided at its top with an annular seat, of a flexible dome-like imperforate cap automatically resuming its normal shape adapted to have its 5 annular edge clamped on said seat and to have the body thereof reversed into the cup without engaging the walls thereof or itself, a ring secured to the end of the cup, said cup and ring being provided with means where-
10 by they can be forced and held together to any extent necessary to secure the cap in place between the cup and ring, forming an air-tight joint for the purpose described, and an inflation valve secured in a wall of the cup whereby the pressure therein may be 15 directly controlled.

In witness whereof, I have hereunto set my hand and affixed my seal, this 26th day of February, A. D. 1921.

EDWARD J. GLACKIN. [L.S.]

Witness:

JOHN HOWARD McELROY.
